Filed Feb. 2, 1959, Ser. No. 54,427

Term of patent 14 years

(Cl. D31—4)

FIG. 1

FIG. 2

FIG. 3

FIG. 4

Fig. 1 is a perspective view on a reduced scale of a combined fishing rod handle, and reel showing my new design, a portion of the rod handle being omitted for convenience of illustration;

Fig. 2 is a left side elevational view thereof with the reel handle rotated approximately 120°;

Fig. 3 is a top plan view of Fig. 2; and

Fig. 4 is a cross-sectional view taken on line 4—4 of Fig. 3, a portion of the reel knob being omitted for convenience of illustration.

The side opposite that shown in Fig. 2 is substantially plain.

I claim:

The ornamental design for a combined fishing rod handle and reel as shown and described.
